L. S. ATKINSON

RAILWAY SIGNALING EQUIPMENT RECEPTACLE

Filed May 14, 1923

INVENTOR.
Lloyd S. Atkinson

BY

Emmett R. Moore

ATTORNEY.

UNITED STATES PATENT OFFICE.

LLOYD S. ATKINSON, OF LAS VEGAS, NEVADA.

RAILWAY-SIGNALING-EQUIPMENT RECEPTACLE.

Application filed May 14, 1923. Serial No. 638,998.

To all whom it may concern:

Be it known that I, LLOYD S. ATKINSON, a citizen of the United States, residing at Las Vegas, in the county of Clark and State 5 of Nevada, have invented new and useful Improvements in Railway-Signaling-Equipment Receptacles, of which the following is a specification.

This invention relates to a novel portable 10 receptacle for a railroad brakeman's signaling equipment.

A main object of my invention is to provide a portable receptacle arranged to conveniently carry and segregate a plurality of 15 different railway signals, so disposed that any one of the signals may be quickly withdrawn from the receptacle without disturbing or disarranging the remainder.

A further object is to provide a device 20 that may be conveniently suspended from the shoulder of a brakeman during a signaling operation, the suspension means not interfering with the withdrawal of the signals from the receptacle when desired.

25 Other objects and advantages will be apparent from the following description, reference being had to the accompanying drawings, in which:

Fig. 1 is a perspective view of my complete device.

Fig. 2 is a central longitudinal section through the same showing the various signals arranged therein.

Fig. 3 is a transverse section taken on line 35 3—3 of Fig. 2.

Fig. 4 is a plan view.

Heretofore railway trainmen, such as brakemen, who have charge of the signaling systems on a train, have had difficulty 40 in readily and quickly procuring the proper signals when needed, the different signals being indiscriminately disposed in a signal box.

By means of my novel form of receptacle, 45 all the different signals are segregated and so disposed that a trainman may readily select any one of the various signals.

In the drawings, 5 designates a rectangular receptacle open at the upper end and provided with a thick bottom wall 6 formed of wood, end walls 7, 8, and wooden side walls 9 that terminate just above the bottom wall, as clearly shown in Figs. 1 and 3 of the drawings. In order to lighten the construction sheet metal walls 10 are secured to the end walls 7 and 8 and extend

downwardly from the upper edge of said end walls and terminate just above the upper edges of walls 9.

Secured to the outer face of end walls 7, 80 8, and preferably at the center thereof, are rail torpedo supporting bars 11, the longitudinally extending corners of the bars adjacent the end walls 7, 8, being cut away to form grooves 12 that are engaged by the 65 spring arms 13 of the torpedoes 14 when disposed thereon, as clearly shown in Figs. 2 and 4 of the drawings.

The interior of the receptacle is provided with a cross partition 16 arranged at one 70 end thereon, dividing the interior of the receptacle into a flag chamber 17, and a fusee compartment 18. Signal flags 19 are disposed within compartment 17 with the flag stick projecting beyond the upper portion 75 of the receptacle in order that it may be quickly withdrawn when desired. In the fusee compartment 18 are disposed a number of fusees 21 provided on their lower ends with spikes 22 which engage the thick bottom wall 6. These fusees, which emit different colored lights when ignited, are utilized by the trainmen as track signals, and are forced into the track bed at a distance 80 from the end of a train when it has stopped 85 for any cause.

At the lower ends of grooves 12 are stops 23 designed to prevent the accidental disengagement of the torpedoes from the bars during the transportation of the equipment 90 receptacle.

In order that the trainmen may conveniently carry the signal receptacle from their shoulders, I have provided the same with a shoulder strap 25, the ends being secured to 95 the upper corners of the side walls 7, 8, the strap passing diagonally over the receptacle. By disposing of the ends of the strap diagonally it will be observed that the device may be conveniently suspended from the 100 shoulder of the trainman, and that it will not interfere with the removal of the signals from the receptacle.

From the above description it will be apparent that I have provided a novel form 105 of receptacle in which may be conveniently disposed a number of railway signals of different varieties required by railroad men in operating trains, and which may be conveniently carried by a trainman when required to leave the train for the placement 110 of signals on the track adjacent the train

without disturbing the arrangement of signals when one of the same is quickly withdrawn therefrom.

What I claim is:

- 5 1. A device of the class described, comprising a rectangular receptacle open at its upper end, and a vertically disposed torpedo supporting member secured to the outer surface of each of the end walls of said receptacle.
- 10 2. A device of the class described, comprising a rectangular receptacle open at its upper end and provided with a partition forming separate chambers, and a vertically disposed torpedo supporting bar mounted
- 15

on the outer surface of each end wall, each of said bars being provided with longitudinally extending grooves for the reception of the torpedo rail securing means.

- 20 3. A railway signal equipment receptacle, comprising a receptacle provided with end, side, and bottom walls, and a rail torpedo supporting bar secured to the outer face of one of the walls of said receptacle, said bar provided on each side with longitudinally extending grooves.
- 25

In witness that I claim the foregoing I have hereunto subscribed my name this 19th day of July, 1923.

LLOYD S. ATKINSON.
